Filed Aug. 12, 1959, Ser. No. 833,247

15 Claims. (Cl. 18—8)

This invention relates to a method of and apparatus for forming continuous filaments or fibers and more especially to the formation of continuous fine filaments of heat-softenable material through the utilization of centrifugal forces.

Methods have been employed for forming filaments of materials such as glass, by attenuation as by winding the filaments in a group or strand on a rotatable collector, the collected group or strand being used in the formation of threads and yarns particularly usable in manufacturing textiles and the like.

Developments have been made in the production of staple filaments or fibers utilizing a rotor fashioned with a substantial number of small openings or orifices through which material is extruded under centrifugal forces of rotation of the rotor and the extruded or projected bodies of material engaged by a gaseous blast for forming the linear bodies into fibers. In such operations the fiber-forming material is heated to a softened or flowable condition in a furnace or feeder and a stream of the softened material delivered into the rotor for extrusion through the perforations or orifices.

The present invention embraces the provision of a method of forming continuous fibers or filaments wherein heat-softenable fiber-forming material is introduced into a rotor in finely divided granular or particulate form and the finely divided or granular material in the rotor subjected to heat in a manner to reduce the material to a liquidous flowable condition and the flowable material acted upon by centrifugal forces to form continuous filaments.

Another object of the invention is the provision of a method involving the delivery of heat-softenable fiber-forming material in a nonmolten condition into a rotating chamber and the material reduced to a molten or flowable state within the chamber and projected from the chamber in the form of discrete bodies through a secondary heated environment in a manner fostering the production of continuous fine filaments from the bodies usable in the production of threads and yarns for textile and similar purposes.

Another object of the invention is the provision of a method of forming continuous filaments by forces of rotation wherein filament-forming material is delivered into a rotatable chamber in a nonmolten condition and the chamber subjected to high frequency electrical energy to heat the material in the chamber to a softened or molten condition and the softened material delivered from the rotating chamber and attenuated to continuous fine filaments.

Another object of the invention is the provision of a method of rapidly reducing finely divided or granular glass cullet to a heat-softened, flowable state within a rapidly rotating chamber including the steps of impinging the granular cullet upon a rotating distributor whereby the cullet is projected to a wall of the chamber, and inductively heating the chamber wall to a temperature above the fusing point of the cullet whereby the cullet at the heated wall is reduced to a heat-softened or molten, flowable condition and the softened material projected by centrifugal forces of rotation from the chamber and attenuated to continuous filaments.

Another object of the invention resides in reducing or

2

converting granules of fiber-forming material to a molten or flowable state within a rotating chamber maintained at a temperature well above the fusing or softening temperature of the material, projecting the heat-softened flowable material through apertures under the influence of centrifugal forces and attenuating the projected material to continuous filaments, and providing a heated atmosphere or environment in the region ambient the chamber and the centrifugally projected material to minimize heat losses at the attenuating region and assist in the collection of the attenuated filaments.

Another object of the invention is the provision of an apparatus comprising a rotatable chamber or rotor of comparatively small diameter heated by high frequency induction and provided with means for distributing granular filament-forming material in a thin layer on a surface of the rotor to reduce the granular material of the layer to flowable form, the rotor provided with open areas through which the flowable material is projected by centrifugal forces and attenuated by rotation of the rotor to form continuous filaments.

Another object of the invention is the provision of an apparatus comprising a rotatable hollow rotor of comparatively small diameter adapted to be rotated at a relatively high speed and inductively heated by high frequency current to fuse the granular material in combination with means for feeding granular material to the rotor at a controlled rate and distributing the material in granular form within the rotor to continuously form a thin layer of the material on the heated rotor surface to rapidly reduce the granular material to a molten state, the arrangement including a plenum chamber surrounding the rotor arranged to deliver air at an elevated temperature and low velocity into an annular region into which molten material is projected and attenuated to continuous filaments to bias the filaments toward a filament collecting means.

Another object of the invention is the provision of a rotor of comparatively small size maintained at a high temperature adapted to reduce granular cullet or material to a heat-softened flowable state, the rotor being provided with orifices through which the softened material is projected in the form of continuous filaments, and means arranged to deliver air streams surrounding the rotor, the air streams being of a temperature to establish an environment of greatest heat adjacent the rotor and a progressively reduced temperature gradient outwardly from the rotor.

Another object of the invention is the provision of a rotatable melting chamber for glass cullet in granular form wherein the rotor providing the chamber is of small diameter and of thin walled construction whereby a minimum of metal is required for the rotor.

Another object of the invention is the provision of a method of forming fibers of heat-softenable mineral material wherein a comparatively small amount of material is rapidly raised to attenuating temperature and immediately converted to continuous filaments, the method being continuous whereby only the amount of material required for immediate attenuation is subjected to intense heat concomitantly with the attenuating operation.

Another object of the invention resides in the provision of a thin walled rotor of comparatively small diameter adapted to receive heat-softenable material in granular form, the rotor being heated by a suitable means to a temperature to rapidly reduce the granular material to a heat-softened state for projection by centrifugal forces of rotation through orifices in the rotor wall, in combination with means for establishing a heated environment within the rotor adjacent the orificed region to maintain the material adjacent the orifices in a heat-softened attenuable condition for delivery through the orifices.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention which may be preferred, in which:

FIGURE 1 is a semi-diagrammatic elevational view illustrating a form of apparatus for performing steps in the method of the invention;

FIGURE 2 is a vertical sectional view through the arrangement illustrated in FIGURE 1;

FIGURE 3 is a horizontal sectional view taken substantially on the line 3—3 of FIGURE 2;

FIGURE 4 is a vertical sectional view illustrating a rotor construction of the invention associated with external heating means and an arrangement for applying heat internally of the rotor;

FIGURE 5 is a fragmentary sectional view similar to FIGURE 2 illustrating a modified form of means for establishing a mobile environment of heated air adjacent and surrounding the rotor, and

FIGURE 6 is an elevational view showing a modified form of rotor.

While the method and apparatus of the invention are especially usable for forming fine continuous filaments or fibers of glass cullet, it is to be understood that the invention may be utilized for forming continuous filaments from other heat-softenable mineral materials or filament-forming resins or polymers.

With particular reference to the apparatus shown in FIGURES 1 through 3, and initially to FIGURE 1, there is illustrated a support or frame construction 10 comprising a main mounting plate 12 to which are secured vertical struts 14 supporting horizontally extending members 16. The plate 12 is provided with a bracket or member 18 which supports an electrical energized motor 20 arranged to rotate the rotor.

Supported upon the mounting plate 12 is a supplemental frame construction 24 having upper and lower members or plates 26 and 28 supporting anti-friction or ball bearings 30 and 32. Journally supported on the bearings 30 and 32 is a rotatable structure including a hollow sleeve 36 of generally circular cylindrical shape formed with a truncated cone shaped or flaring portion 38 joined with a depending cylindrical wall portion 40 adapted to support the rotor construction.

With particular reference to FIGURE 2, the rotor or rotor construction 44 is of tubular thin walled configuration comprising a vertically disposed circular cylindrical wall 46 and bottom wall 48, the rotor being made of platinum rhodium alloy or other material which will withstand high temperatures. The upper end of the wall 46 is formed with an outwardly extending circular flange 52 and an inwardly extending flange 50. Means is provided for connecting the rotor 44 with the cylindrical sleeve portion 40.

As shown in FIGURE 2, a coupling or collar 54 of cylindrical shape is fashioned with an inwardly extending flange 56 which is joined to the flange 52 of the rotor by means of pins 58 or other suitable securing means adapted to establish a drive connection between the rotor 44 and the coupling member 54. The depending sleeve portion 40 is formed with circumferentially spaced bayonet-type slots 62 and the upper region of the coupling member 54 provided with pins 64 adapted to establish, with the slots 62, a driving connection between the journally supported sleeve 36 and the coupling member 54.

A locking ring 66 surrounds the sleeve portion 40 and is vertically slidable relative thereto for engagement with the upper region of the coupling 54 to prevent relative rotation between the sleeve portion 40 and the coupling 54 in driving engagement through the pin and slot con-

nection. The sleeve 36 is equipped with pulley 70 engaged by a driving belt 72 driven by the motor 20 through a motor driven pulley 74 as shown in FIGURE 1.

The circular cylindrical wall 46 of the rotor 44 is of comparatively small diameter, for example, 1 1/4" inside diameter whereby the rotor may be driven or rotated at a comparatively high speed to set up or establish centrifugal forces of sufficient magnitude to effectively and efficiently project heat-softened mobile material within the rotor through rows of small orifices 49 formed in the lower region of the cylindrical rotor wall 46. Any number of small orifices 49 may be employed, dependent upon the number of continuous filaments to be formed.

The orifices 49 are of small size in order to provide for the formation of fine continuous filaments from the streams of heat-softened material moving through the orifices. If a greater number of continuous filaments is desired to be produced from one rotor, a greater number of orifices may be employed by increasing the diameter of the rotor wall 46 or employing a rotor of increased length.

An important feature of the method of the invention resides in the delivery into the rotor of fiber-forming material in finely divided, particulate or granular condition at normal temperature and the granular material distributed onto the rotor wall 46 which is heated and maintained at a temperature sufficiently high to rapidly fuse or reduce the particles or granules to a heat-softened mobile or molten condition. The fiber-forming material is delivered in particulate or granular form into the interior of the rotor through the hollow sleeve 36. Disposed within the rotating sleeve 36 is a stationary guide means for directing the particulate or granular material into the rotor.

As shown particularly in FIGURE 2, the guide means comprises a tube 76 surrounded by a jacket 78 having a closed lower end 79 to accommodate a cooling fluid. This arrangement provides an elongated annular chamber 80 to accommodate a circulating cooling fluid which is introduced into the chamber through an inlet 82 and conveyed away from the chamber by an outlet 84. The circulation of cooling fluid through the chamber 80 is effective to maintain the guide tube 76 and the sleeve 36 at safe operating temperatures.

Means is provided for feeding the particulate or granular material such as crushed glass cullet into the guide means 76. As shown in FIGURE 1, a hopper 86, adapted to contain a supply of the particulate or granular material, is disposed above a funnel or chute 88 supported by the frame structure 10, the chute 88 being adapted to direct the fiber-forming material into the guide tube 76. The hopper 86 is formed with a discharge tube 90 in registration with the chute 88 for delivering material into the funnel 88.

Means is provided associated with the hopper 86 for controlling or regulating the rate of feed or delivery of the particulate or granular material into the rotor. As shown in FIGURE 1, the hopper 86, at its region of connection with the discharge tube 90, is formed with a cylindrically shaped portion 92 in which is journalled a shaft 93 carrying a feed drum 94 provided with radially arranged vanes 95, the vanes having rotating clearance with the cylindrical portion 92 of the hopper. The rotating vanes 95 engage material in the hopper and convey successive metered quantities of material into the tube 90.

A sprocket on the shaft 93 is connected by means of driving chain 98 with a sprocket 99 associated with speed reducing gearing contained in a housing 100, the gearing being operated by an electric motor 102 for driving the material feed or metering drum 94. The gearing within the housing 100 may be of the variable speed type to vary the rate of rotation of the feed drum, or other suitable variable speed driving means may be utilized for rotating the drum 94.

Positioned within the rotor 44 is a platform or material

distributing member 106 preferably slightly frusto-conical in shape, as shown in FIGURE 2, the platform being of circular contour and supported by radially extending struts or bars 103, shown in FIGURE 3, welded or otherwise joined to the inner surface of the vertical rotor wall 46 and to the peripheral region of the distributing plate 106, the member 106 being rotatable with the rotor.

The struts 103 are fashioned comparatively thin so as not to appreciably impair or impede the formation of a film of heat-softened material on the inner cylindrical surface of the rotor wall 46. The finely divided material M descending by gravity through the guide tube 76, as shown in FIGURE 2, impinges or engages the rotating distributing plate 106, the particulate or granular material being projected outwardly by centrifugal forces into contact with the inner surface of the vertical wall 46 of the rotor. In the arrangement illustrated in the drawings, comparatively high frequency electric current is employed for inductively heating the rotor or spinner to a temperature sufficiently high to rapidly fuse or reduce the particulate or granular material to a heat-softened flowable condition whereby a film of mobile heat-softened or molten material is provided and continuously maintained on the interior surface of the rotor wall 46. As shown in FIGURES 1, 2 and 3, an induction heating coil 110 surrounds the vertical wall 46 of the rotor at a region just above the uppermost row of orifices or outlets 49, the leads 112 and 114 from the induction coil being connected with a power supply 116, indicated schematically in FIGURE 1, of a character to produce a current of high frequency of ten thousand cycles or more per second supplied to the heating coil 110. The metal conductors of the coil are hollow and are water cooled. The convolutions of the coil 110 are provided with a sheath or coating of glass fibers and resin to insulate the convolutions, one from another.

By supplying high frequency current to the coil 110 the rotating rotor 44 is heated to a temperature of twenty-five hundred degrees Fahrenheit or more, sufficiently high to fuse or soften the granular material collecting on the vertical wall 46.

The rotor 44 is rotated at a speed of upwards of seven thousand revolutions or more per minute depending upon the diameter of the rotor and the desired magnitude of centrifugal forces set up by rotation acting upon the film of flowable softened glass at the region of the orifices 49 whereby the softened material is projected outwardly and attenuated by the centrifugal forces and the rotative movement of the rotor to form fine continuous filaments F.

The filaments are directed downwardly by means hereinafter described and are brought together at a region 120 to form a twisted multifilament strand, thread or yarn 122 which may be collected upon a rotating collector sleeve or member 124 carried by a rotating mandrel 126. The multifilament strand may be traversed lengthwise of the collector sleeve 124 by suitable conventional traverse means (not shown) to form a wound package.

In order to direct the discrete continuous filaments downwardly from the rotor and to promote efficient attenuation an environment of heated air is provided at the exterior surface region of the rotor wall 46 and the region occupied by the outwardly moving continuous filaments. The heated air is continuously delivered into the environment surrounding the rotor at a comparatively low flow rate to form a downwardly moving heated air stream in the nature of a gentle breeze to gradually retard outward movement of the continuous filaments and assist in directing the filaments downwardly in the general path illustrated in FIGURES 1 and 2.

In the arrangement illustrated in FIGURES 1 and 2, an annularly shaped member 130 disposed concentric with the axis of the rotor is formed with an annular plenum chamber or manifold 132, the member being supported by brackets 131 associated with member 12. The plenum chamber 132 is connected by means of tubular means

134 with a heating chamber 136 into which atmospheric air is delivered by means of a blower 138 and a conduit 140. The heating chamber 136 is provided with electrically energized heater strips or units 142 adapted to heat the incoming air admitted through the duct or conduit 140 before the air is delivered into the plenum chamber 132.

Other types of air heating means may be employed for the purpose. A lower wall 144 and an angularly arranged or frusto-conically shaped wall 146 are provided with one or more rows of openings 148 and 150 respectively as shown in FIGURE 2. The openings 150 in the wall 146 are arranged to direct air toward the rotor wall 46 while the openings 148 in the wall 144 direct air into the environment occupied by the filaments moving outwardly from the rotor.

The heater 136 is adapted to heat the air delivered from the plenum chamber 132 at a temperature of about 500° F. or more and, through this method, the filaments move through a heated environment as they are attenuated, the heated environment assisting in retarding or minimizing heat losses from the rotor. The low velocity air streams from the outlets 148 and 150 provide a biasing force effective to influence movement of the individual attenuated continuous filaments in a downward direction.

The heated environment provided by flow of air from the plenum chamber 132 is preferably surrounded by a second annular environment of heated air of a lower temperature than that delivered from the plenum chamber 132. As shown in FIGURE 2, a second annular or ring-shaped member 154, supported by the member 12, surrounds the plenum chamber 132 and is formed with a plenum chamber 155 adapted to receive atmospheric air supplied by a blower 156 through a conduit 158. The air from the blower 156 may be heated in a chamber 157 by electrically energized heater strips 159 adapted to heat the air in the chamber 155 above room temperature but at a temperature lower than the air delivered from the first plenum chamber 132.

Baffle members 160 are disposed in the annular manifold or chamber 155 to distribute the heated air throughout the chamber. The floor or lower wall of the chamber 155 is in the form of a perforated grill or plate 162, the air from the chamber 155 being projected at a low velocity through the plurality of openings 164 formed in the grill or plate 162. The air flow from the chamber 155 provides an environment surrounding the first mentioned environment of heated air at a lower temperature to assist in deflecting or directing the continuous filaments downwardly.

A cylindrically shaped shield or enclosure 168, secured to and depending from the periphery of the annular manifold 154, provides a barrier or means for confining the environment of heated air, and influencing movement of the heated air in a downward direction causing the continuous filaments F to be directed downwardly in directions illustrated in FIGURES 1 and 2.

Through the arrangement of the plenum chambers 132 and 155 adapted to deliver heated air of different temperatures into the circular enclosure 168, a decreasing temperature gradient is established outwardly of the axis of the rotor 44.

The method of operation of the arrangement shown in FIGURES 1 through 3 is as follows: The hopper 86 is filled with heat-softenable fiber-forming material in finely divided, particulate or granular form. Where the fiber-forming material to be employed is glass, the glass is highly refined and previously formed into pieces or marbles which are ground or crushed to granular or particulate form.

The rotor 44 is rotated by energizing the motor 20 to revolve the rotor at a speed of upwards of seven thousands revolutions per minute or more to develop centrifugal forces effective to cause the extrusion or projection of heat-softened material of the film of molten material in

the rotor through the orifices 49 in the rotor wall 46. High frequency current energizes the induction heater 110 surrounding the rotor to heat that region of the rotor surrounded by the induction heater to a temperature of 2500 degrees Fahrenheit or more. The blowers 138 and 156 are rotated to deliver air into the heating chambers 136 and 157.

The heater strips 142 in the chamber 136 are energized to heat the air in the unit 136 to a temperature upwards of 500° F. or more and under the pressure of the blower 138 the heated air flows through conduit 134 into the plenum chamber 132 thence through the orifices 148 and 150 in wall regions of the annular member 130 providing the plenum chamber 132, whereby the heated air moves at a low velocity downwardly along the rotor and in the annular region or environment surrounding the rotor.

The heater strips 159 in the chamber 157 are energized to heat the air delivered through the perforations or outlets 164 at a lesser temperature than the air from the plenum chamber 132. The air delivered through the outlets 164 is preferably between 100 and 300 degrees Fahrenheit but is not limited to this temperature range. The air delivered from the chamber 155 assists in deflecting the continuous filaments F downwardly as well as to maintain the heated air from the chamber 132 in a region ambient the rotor to retard or prevent rapid chilling of the fiber-forming material. A second water cooled induction heating coil 166 may be disposed interiorly of the skirt or sleeve 168 surrounding and in horizontal alignment with the region of the rotor provided with the orifices 49 for heating this portion of the rotor. The induction heater 166 may be energized by high frequency current from the generator or power supply 116.

The motor 102 is energized to operate the feed drum or rotary valve 94 disposed in the lower region of the hopper 86 so as to continuously meter and feed the particulate or granular fiber-forming material from the hopper 86 into the tube 90 and chute 88, through the guide tube 76 and onto the platform or material distributor 106 arranged in the path of the material moving through the tube 76. The centrifugal forces of rotation of the distributor 106 deliver the particulate or granular material outwardly into contact with the interior surface of the rotor wall 46 or in contact with material on the wall which has been heat-softened under the intense heat of the rotor wall generated by high frequency current in the induction heater 110.

Thus, the finely divided fiber-forming material at the inner surface of the rotor wall 46 is rapidly heated and reduced to softened, flowable or mobile form providing a thin film of molten material on the interior surface of the wall 46.

The inwardly extending ledge or flange 50 at the upper end of the rotor limits the upward movement of the flowable material and under the influence of centrifugal forces the softened flowable material of the film is continuously projected or extruded outwardly through the outlets or orifices 49 as individual bodies, and under the influence of centrifugal forces and rotation of the rotor, the bodies of material are attenuated to fine continuous filaments F.

The gentle air currents delivered downwardly from the outlets from the plenum chambers 132 and 155 assist in deflecting the continuous filaments downwardly. By reason of rotation of the rotor, the group of continuous filaments is twisted together at the region 120 forming a linear group, strand or yarn 122 of filaments which is collected upon the rotating sleeve or collector 124 carried by the mandrel 126. The rate of feed of the finely divided or particulate material delivered from the hopper 86 may be regulated and controlled through the variable speed mechanism contained in the housing 100 of the means driving the material metering or feed valve 94.

Through this method and apparatus of forming continuous filaments, the finely divided material is delivered into intimate contact with the intensely hot rotor wall 46 and is rapidly heated to a softened and flowable condition in a zone where the heat is concentrated through the use of high frequency current in the induction heater 110 with a minimum of heat loss. The heated air from the plenum chamber 132 assists in maintaining the rotor at a high temperature by surrounding the rotor with an environment of heated air whereby a high efficiency of attenuation is attained.

The use of a comparatively small rotor effects substantial savings in platinum rhodium alloy which is very costly. Furthermore the method eliminates the use of a stationary feeder containing a substantial quantity of glass which must be maintained at a high temperature to supply streams of molten glass for attenuation purposes. Through the method of the present invention, the glass cullet is heated in the rotor to a molten state and only 10 the amount of cullet is heated to provide a thin film of molten glass on the rotor surface to fulfill the requirements necessary to maintain continuous delivery of softened glass through the rotor orifices 49.

FIGURE 4 is a sectional view illustrating a modified form of rotor in conjunction with means for applying heat interiorly of the rotor supplementing the heat derived from high frequency induction. In this form, the rotor 170 is formed with a bottom wall 171 and a cylindrical vertical wall 172 provided at its upper end with 25 an outwardly extending annular flange 173 and an inwardly extending annular flange 174. The wall 172, at its lower region, is provided with a plurality of rows of orifices 176 through which heat-softened or molten material of the film of material on the inner surface of the wall 172 is projected by centrifugal forces and attenuated to continuous filaments.

The rotor 170 is formed with an axially disposed strut 178 which supports a platform or material distributing member 180 which is similar to the material distributor 40 106 shown in FIGURE 3. The material guide tube 76a is aligned with the distributor 180 whereby fiber-forming material in finely divided or particulate form delivered onto the distributor 180 is subjected to centrifugal forces of rotation of the distributor and thereby projected outwardly onto the inner surface of the rotor wall 172.

Extending downwardly into the rotor 170 is a tubular means 182 having a curved outlet or elbow portion 184 at its lower extremity, as shown in FIGURE 4, directed toward the lower peripheral region of the wall 172 adjacent its juncture with the bottom wall or floor 171 of the rotor. The tubular means 182 is adapted to be connected with a supply of combustible mixture, such as fuel gas and air, under comparatively low pressure which is conveyed from the supply by the tubular means for 50 discharge from the curved or elbow portion 184 into the rotor.

The combustible mixture is ignited at the outlet of the curved portion 184 and provides heat in the lower interior peripheral region of the rotor to assist in maintaining the heat-softened film of fiber-forming material in the rotor in a flowable condition to facilitate its delivery through the orifices 176. The rotor 170 is heated by high frequency current supplied to the induction heater 110a, and the supplemental heat, provided by the burning mixture at the outlet of the portion 184, avoids any tendency of the material in the lower region of the rotor from becoming highly viscous, a condition which would impair the flowability of the material.

FIGURE 5 is a fragmentary sectional view similar to 70 a portion of FIGURE 2 illustrating a modified arrangement of plenum chambers for providing successive environments of air at different temperatures at the region of formation of the continuous filaments. In this form, the rotor 44a and its driving means are the same as the 75 means illustrated in FIGURE 2.

The annular manifold 130a, the annular plenum chamber 132a and the air discharge orifices 148a and 150a are of the same character as those shown in FIGURE 2. The plenum chamber 132a receives heated air from the air heating unit 136a whereby air at upwards of 500° F. or more is delivered into a region surrounding and adjacent the rotor 44a.

A second manifold 186 is disposed adjacent manifold 130a and at a lower level than the manifold 130a, the inner circular wall 188 of the manifold 186 forming a means of confining the heated air delivered through the orifices 148a and 150a adjacent the rotor. The member or manifold 186 is formed with an outer peripheral wall 190 which supports a cylindrical sleeve, guard or baffle 168a. The member 186 is provided with a circular partition 192 which effectively subdivides the hollow interior of member 186 into a plenum chamber 194 and a second plenum chamber 196 which are arranged in concentric relation.

A plate 198 forms a bottom wall of both chambers and is formed with a comparatively large number of small outlets or orifices 200 through which air from chambers 194 and 196 is delivered within the region defined by the circular sleeve 168a. The plenum chamber 194 is supplied with air from a blower (not shown) the air being conducted through a heater 157a for heating the incoming air to a temperature lower than that of the heated air supplied to the chamber 132a.

The chamber 196 is adapted to deliver air at room temperature through a tube 206 connected with a suitable blower (not shown) to provide a low velocity air movement surrounding the heated air environment. The chambers 194 and 196 may be provided with baffles 209 and 210 respectively to assist in the distribution of air in the chambers.

Thus, through the arrangement of plenum chambers 132a, 194 and 196 adapted to deliver air at different temperatures, a temperature gradient is established in the environment surrounding the rotor with progressively lower temperatures maintained at increased distances outwardly from the rotor. The highest temperature environment is established at the region of the rotor 44a and low velocity air streams flowing from the plenum chambers deflect the continuous filaments F downwardly.

A modified form of rotor 216 is illustrated in FIGURE 6. The rotor 216 is formed with a wall 218 tapered or flared outwardly and downwardly from the flange 220 to assist in biasing the flow of the molten material of the film adjacent the inner surface 222 toward the region of the orifices 224. While a single row of orifices is illustrated in FIGURE 6, it is to be understood that a plurality of rows may be utilized dependent upon the number of filaments desired to be formed from a single rotor.

The lower region of the rotor beneath the tapered wall 218 is formed with a cone-shaped portion or cap 226 to reduce turbulence immediately beneath the rotor.

In the forms of the rotor construction, the platform or material distributor is at the upper region of the rotor and is substantially embraced by the induction heating unit so that the glass cullet is distributed to the rotor wall at a region of high temperature in order to efficiently reduce the particles to molten condition. It is to be understood that while the method and arrangement are particularly adapted for reducing granular or particulate filament-forming material to a softened and flowable condition, a stream of heat softened glass or other mineral material may be delivered through the guide tube onto the platform and the softened material distributed on the rotor wall.

It will be apparent that, within the scope of the invention, modifications and different arrangements may be made other than as herein disclosed, and the present disclosure is illustrative merely, the invention comprehending all variations thereof.

We claim:

1. The method of processing heat-softenable filament-forming material including the steps of feeding the material onto an elevated platform in a walled chamber, distributing the material from the platform by centrifugal forces toward a wall of the chamber to form a thin layer of the material on the wall, inductively heating the chamber, reducing the material to molten condition by the inductive heat applied to the chamber, flowing the molten material downwardly along the wall, rotating the walled chamber at a high speed, projecting the molten material by centrifugal forces of rotation from the chamber through openings in the chamber wall, attenuating the projected material to continuous filaments by rotation of the chamber.
- 5 2. The method of processing heat-softenable filament-forming material including the steps of feeding the material in particulate form onto an elevated platform in a walled chamber, distributing the material from the platform to form a thin layer of the material on the wall, applying electric heat to the chamber, reducing the particles to molten condition by the heat applied to the chamber, flowing the molten material downwardly along the wall, rotating the walled chamber at a high speed, projecting the molten material by centrifugal forces of rotation outwardly from the chamber through openings in the chamber wall, attenuating the projected material to continuous filaments by rotation of the chamber, and engaging the filaments by downwardly directed low velocity air streams to modify the directions of movement of the continuous filaments.
- 10 3. The method of processing heat-softenable filament-forming material including the steps of feeding the material onto an elevated platform in a walled chamber, distributing the material from the platform toward a wall of the chamber to form a thin layer of the material on the wall, applying heat to the chamber, reducing the material to molten condition by the heat applied to the chamber, flowing the molten material downwardly along the wall, rotating the walled chamber at a comparatively high speed, projecting the molten material by centrifugal forces of rotation outwardly from the chamber through openings in the chamber wall, attenuating the projected material to continuous filaments by rotation of the chamber, directing low velocity heated air streams in the region of the continuous filaments, and deflecting the continuous filaments downwardly and away from the chamber by the air streams.
- 15 4. The method of processing heat-softenable filament-forming material including the steps of feeding the material from a supply at a controlled rate into contact with a movable distributor, delivering the material from the distributor onto a rotating surface to form a thin layer of the material on the surface, continuously heating and maintaining the surface at a temperature above the softening temperature of the material, reducing the material on the surface to a molten condition by heat from the surface, rotating the surface at a high speed, projecting the molten material through openings in the rotating surface, attenuating the projected material to continuous filaments, and directing air streams of different temperatures into the region of the continuous filaments to establish a decreasing temperature gradient outwardly from the rotating surface.
- 20 5. The method of processing heat-softenable filament-forming material including the steps of feeding the material in particulate form from a supply at a controlled rate, delivering the material from the distributor onto a surface to form a thin layer of the material on the surface, continuously heating and maintaining the surface at a temperature above the softening temperature of the material, reducing the particles of material on the surface to a molten condition by heat from the surface, rotating the surface at high speed, projecting the molten material through openings in the rotating surface, attenuating the

projected material to continuous filaments, directing air streams at elevated temperature into the zone of the moving filaments, and directing air streams of lesser temperature into a zone surrounding the air streams at elevated temperature to establish a decreasing temperature gradient outwardly of the axis of rotation of the surface.

6. The method of processing heat-softenable filament-forming material including the steps of feeding the material from a supply at a controlled rate into contact with a movable distributor, delivering the material from the distributor to a wall of a chamber to form a thin layer of the material on the wall surface, inductively heating and maintaining the surface at a temperature above the softening temperature of the material, reducing the material on the surface to a molten condition by heat from the surface, rotating the chamber, projecting the molten material through openings in the wall of the chamber, attenuating the projected material to continuous filaments, directing air streams of low velocity at elevated temperature into the zone of the moving filaments adjacent the surface, and directing air streams of lesser temperature and of low velocity into a zone surrounding the air streams at elevated temperature to establish a progressively decreasing temperature gradient outwardly of the axis of rotation of the chamber.

7. The method of processing heat-softenable, filament-forming material including the steps of establishing a supply of the material in particulate form, feeding the material from the supply at a controlled rate onto an elevated platform in a walled chamber, distributing the material in particulate form by centrifugal force from the platform into heat-transferring relation with the chamber wall, heating the chamber wall inductively by high frequency current to a temperature above the softening temperature of the material, reducing the material to a molten condition by heat from the wall of the chamber, flowing the molten material downwardly along the wall, rotating the walled chamber at a high speed, projecting the molten material through orifices in the wall under the influence of centrifugal forces, attenuating the projected material to fine continuous filaments by rotation of the walled chamber, and directing the continuous filaments downwardly by low velocity streams of air.

8. The method of processing heat-softenable, filament-forming material including the steps of establishing a supply of the material, feeding the material from the supply at a controlled rate onto an elevated platform in a walled chamber, distributing the material by centrifugal forces from the platform into heat-transferring relation with the chamber wall, continuously heating the chamber wall inductively by high frequency current to a temperature above the softening temperature of the material, reducing the material to a molten condition by heat from the wall of the chamber, flowing the molten material downwardly along the wall, rotating the walled chamber at a high speed, applying additional heat to the material interiorly of the chamber, projecting the molten material through orifices in the wall under the influence of centrifugal forces, attenuating the projected material to fine continuous filaments by rotation of the walled chamber, biasing the continuous filaments downwardly by concentric streams of heated air, and collecting the continuous filaments in a linear group.

9. The method of processing heat-softenable filament-forming material including the steps of feeding the material in finely divided form into engagement with a distributor in a walled chamber, discharging the finely divided material from the distributor by centrifugal forces into engagement with a surface of the walled chamber, heating the chamber by high frequency current to maintain the temperature of the surface above the softening temperature of the finely divided material, softening the material on the surface by the heat to a flowable state, rotating the chamber, flowing the softened material down-

wardly along the surface, flowing the softened material through openings in the surface under the influence of centrifugal forces and attenuating the material into discrete continuous filaments, continuously flowing heated air at low velocity in a region surrounding the chamber, modifying the directions of movement of the continuous filaments by the heated air, and collecting the continuous filaments in a linear group.

10. The method of processing heat-softenable filament-forming material including the steps of feeding the material in finely divided form into engagement with an elevated distributor in a walled chamber, discharging the finely divided material from the distributor by centrifugal forces into engagement with a surface of the walled chamber, heating the chamber by high frequency current to maintain the temperature of the surface above the softening temperature of the finely divided material, softening the material on the surface by the heat to a flowable state, rotating the chamber, flowing the material downwardly along the surface, flowing the softened material through openings in the surface under the influence of centrifugal forces to form the material into discrete continuous filaments, continuously flowing low velocity streams of heated air in a region adjacent and surrounding the chamber, continuously flowing low velocity streams of air of a lesser temperature in an annular region surrounding the heated air adjacent the rotor, retarding movement of the continuous filaments outwardly from the chamber by the air streams, and collecting the filaments in a twisted linear group.

11. Apparatus of the character disclosed including, in combination, a support, a thin-walled hollow rotor of small diameter and of generally cylindrical shape journally supported for rotation on the support, means for rotating the rotor, said rotor wall being formed with a plurality of comparatively small orifices, a platform in said rotor rotatable with the rotor, means for feeding heat-softenable material into the rotor onto the platform, said platform being arranged to distribute the material onto the wall region of the rotor, means for heating the rotor to a temperature sufficient to reduce the material to a molten condition, said rotor being rotated at a speed to project the molten material by centrifugal forces through the orifices as continuous filaments, a plenum chamber disposed adjacent the rotor having an open area adapted to direct low velocity streams of air into the zone of the continuous filaments, means for heating the air prior to its delivery from the plenum chamber, and a barrier surrounding and spaced from the rotor arranged to confine the heated air in the zone of the filaments.

12. Apparatus of the character disclosed including, in combination, a support, a thin-walled hollow rotor of comparatively small diameter journally supported for rotation on the support, means for rotating the rotor, said rotor wall being formed with a plurality of comparatively small orifices, means for feeding heat-softenable material into the rotor in particulate form, means within the rotor arranged to distribute the material onto a wall region of the rotor, a first high frequency induction heating means for heating a wall region of the rotor spaced from the orifices to a temperature sufficient to reduce the particles of material to a molten condition, said rotor being rotatable at a speed to project the molten material by centrifugal forces through the orifices as continuous filaments, a plenum chamber disposed adjacent the rotor having an open area adapted to direct streams of air into the zone of the continuous filaments, and means for heating the air prior to its delivery from the plenum chamber, a sleeve surrounding and spaced from the rotor arranged to confine the heated air in the zone of the filaments, and a second high frequency induction heating means surrounding the rotor and spaced from said first induction heating means for heating the wall region of the rotor provided with the orifices.

13. Apparatus of the character disclosed including, in

combination, a support, a thin-walled hollow rotor of comparatively small diameter journally supported for rotation on the support, means for rotating the rotor, a wall of said rotor being of frusto-conical shape formed with a plurality of orifices, an elevated platform in the rotor rotatable with the rotor means for feeding heat-softenable material into the rotor in particulate form onto the platform, said platform being arranged to distribute the material onto frusto-conical wall of the rotor, high frequency induction means for heating the rotor to a temperature sufficient to reduce the particles of material to a molten condition, said rotor being rotatable at a speed to project the molten material by centrifugal forces through the orifices as continuous filaments, a plurality of annular plenum chambers disposed in concentric relation having open areas adapted to direct low velocity streams of air into the zone of the continuous filaments, heating means for elevating the temperature of the air prior to its delivery from the plenum chambers, and a member surrounding and spaced from the rotor arranged to confine the heated air in the zone of the filaments.

14. Apparatus of the character disclosed including, in combination, a support, a thin-walled hollow rotor journally supported for rotation on the support, means for rotating the rotor, said rotor wall being formed with a plurality of small orifices, an elevated platform in the rotor rotatable with the rotor, means for feeding heat-softenable material into the rotor in particulate form onto the platform, said platform being arranged to distribute the material onto a wall region of the rotor, a high frequency induction heating means surrounding the rotor arranged to heat the wall region of the rotor to a temperature above the softening temperature of the material to reduce the material on the wall region to a molten condition, a cylindrical sleeve spaced from and surrounding the rotor, means for rotating the rotor to project the flowable material through the orifices under the influence of centrifugal forces to form continuous filaments, a plenum chamber substantially concentrically arranged with respect to the rotor, said plenum chamber being adapted to deliver low velocity streams of air into

the region of the continuous filaments, means associated with the plenum chamber for elevating the temperature of the air prior to its delivery from the plenum chamber to establish a heated environment for the continuous filaments.

15. Apparatus of the character disclosed including, in combination, a support, a thin-walled hollow rotor of comparatively small diameter journally supported for rotation on the support, means for rotating the rotor, said rotor wall being formed with a plurality of comparatively small orifices, an elevated platform in the rotor rotatable with the rotor, means for feeding heat-softenable material into the rotor onto the platform, said platform being arranged to distribute the material onto a wall region of the rotor, a high frequency induction heating unit surrounding the rotor and arranged to heat the wall region of the rotor to a temperature above the softening temperature of the material to reduce the material on the wall region to a molten condition, means for rotating the rotor to project the molten material through the orifices under the influence of centrifugal forces to form continuous filaments, and a plurality of annularly shaped plenum chambers substantially concentrically arranged with respect to the rotor, said plenum chambers being adapted to deliver low velocity streams of air into the region of the continuous filaments.
